METHOD OF TREATING PLISSÉ CREPE

Frank C. Hewitt, Northampton, Mass., assignor to
 Hampton Company, Easthampton, Mass., a corporation of Massachusetts

Application January 29, 1940, Serial No. 316,143

1 Claim. (Cl. 223—28)

This invention relates to a method of processing plissé crepe fabrics and has particular reference to a treatment of its unshrunk selvages as the crepe passes from the tenter frame in order to cause the material to lie flat.

In the making of plissé crepe the fabric is subjected to a shrinking process, and is then dried out and stretched on a tenter frame. During this process the selvages of the fabric are not shrunk to the same degree as the body of the web, and after the fabric is stretched on the tenter frame the selvages of the crepe are materially longer than the body of the fabric itself. This causes the crepe to be uneven. Measurement of the cloth along the selvage does not truly reflect the correct measure, of length. Difficulty is also encountered when the crepe is rolled, the longer selvages making the rolling awkward and the roll itself uneven, tending to increase in diameter at its ends.

An object of this invention is to correct the undesirable features of a longer selvage. The manner in which this problem has been met may best be understood in connection with the drawing, in which

Fig. 1 is a perspective view of a roll of crepe, the ends of the roll being humped because of the longer selvages;

Fig. 2 is a diagrammatic elevation of the roller mechanism designed to treat the selvages of plissé crepe;

Fig. 3 is a fragmentary elevation on a larger scale of one end of the rollers with a piece of crepe therebetween;

Fig. 4 is an end view of the rollers showing the action of the rollers on the selvage; and

Fig. 5 is a fragment of plissé crepe showing a processed selvage.

The crepe 1 as it comes from a tenter frame (not shown) enters the bight of rollers 2 and 3 mounted in supports 4. The rollers are driven at uniform surface speeds by any gearing mechanism (not shown) suitable for that purpose. Top roller 2, preferably smaller than roller 3, is covered, for a purpose to be later described, with a matted or fibrous material such as felt covering 5, seen in Fig. 4. Roller 3 is of metal such as chilled iron, with a slightly concave surface, as

seen by lines 6. The concavity has been greatly exaggerated for clarity, in the actual structure being scarcely perceptible to the eye.

As the crepe enters the bight of the rollers 2 and 3 no pressing or flattening action on the body of the fabric results because of the concave surface of roller 3 and the slight separation of the rolls. Roller 2, because of frictional engagement with the crepe, causes the crepe to be fed at a uniform rate, related to and governed by the length of the fabric itself and not by the longer selvages. The body of the fabric then will tend to force the selvages to accumulate or pile up before entering the bight of the rollers and then to fold over and crease as they are carried through. This folding is completed, and the pleats are ironed down, when the selvage passes between the rollers. As seen in the exaggerated view of Fig. 3, the edges of the rollers are in close proximity to each other and a pressing and ironing action takes place, on the selvage, being more pronounced because of the increased thickness of the bunched and folded over portions. As seen in Fig. 4 (also exaggerated), the folds have been ironed down and the selvage is pleated irregularly as in Fig. 5. These irregular pleats 7 have shortened the selvage to a length equal to the body of the fabric itself, since the pleats are formed with relation to the length of fabric passing between rollers 2 and 3.

The plissé crepe with pleated edges can then be measured and rolled evenly and with accuracy. The humps on the ends of the roll of Fig. 1 will disappear and a uniform length is obtained.

I claim:

An apparatus for reducing the length of the selvages of plissé crepe to correspond with the length of the body of the fabric, comprising a hard-surfaced roll concave in its central portion, and a felt-covered roll in pressing and feeding contact therewith, the rolls being separated sufficiently one from another to cause them to draw the creped body of the fabric by frictional contact and without substantial pressure, and sufficiently close to iron down the pleats formed by the unshrunk selvages as they pass between the rolls.

FRANK C. HEWITT.
